TUBING CATCHER

Homer H. Hall, Tulsa, Okla., assignor to James B. Duff, Tulsa, Okla.

Application November 26, 1937, Serial No. 176,517

11 Claims. (Cl. 103—219)

This invention relates to new and useful improvements in tubing catchers.

As is well known, it is the usual practice to connect a tubing catcher in the tubing string 5 of a well and lower the same with said string into the well casing. In the event that the tubing should break, the catcher is operated to grip the well casing and prevent falling of the broken tubing string to the bottom of the casing. The majority of tubing catchers, which are now on the open market, are constructed in various sizes to fit tubing and casing of varying diameter. When the size of the tubing or casing is changed, it is necessary that the size of the 10 tubing catcher be changed, which causes a well operator to maintain a supply of tubing catchers of various sizes to take care of changes in the diameter of the tubing and casing.

It is one of the objects of this invention to 20 provide an improved tubing catcher which may, with slight changes, be employed with well tubing and casing of various diameters, whereby a single catcher may be utilized in different size pipe, within certain limits.

25 An important object of the invention is to provide an improved tubing catcher having a removable slip head on which gripping slips are slideable, the removability of said head making it possible to change or replace the same with a head of a different size, whereby the size of the 30 catcher with relation to the well casing diameter may be readily varied to permit the catcher to be used within well casings of different sizes.

Another object of the invention is to provide 35 an improved tubing catcher which is adapted to be connected in a well tubing; the connections by which said tubing is secured to the catcher being readily removable, whereby said connections may be replaced by connections of other 40 sizes to accommodate tubing of various diameters, thereby making the catcher applicable to different size tubing.

A further object of the invention is to provide 45 a tubing catcher, of the character described, wherein a section of the well tubing may be utilized as the supporting mandrel of the catcher, whereby the tubing and mandrel are of the same diameter.

A particular object of the invention is to provide 50 an improved tubing catcher having a slip head on which gripping slips are slideable, said head having inserts therein on which said slips are movable; the removability of said inserts making it possible to readily replace the same 55 with inserts of any size to permit the catcher

to be used in well casings of various diameters.

A construction designed to carry out the invention will be hereinafter described, together with other features of the invention.

The invention will be more readily understood 5 from a reading of the following specification and by reference to the accompanying drawings, in which an example of the invention is shown, and wherein:

Figure 1 is a view, partly in elevation and 10 partly in section, of a tubing catcher, constructed in accordance with the invention.

Figure 2 is a horizontal, cross-sectional view, 15 taken on the line 2—2 of Figure 1.

Figure 3 is a view similar to Figure 1 and 20 showing the tubing catcher used with tubing and casing of a different diameter.

Figure 4 is a view, partly in elevation and 25 partly in section, of a modified form of the invention.

Figure 5 is a view, similar to Figure 4, with 30 the device applied to tubing of a different diameter, there being a slight modification in the fishing neck.

Figure 6 is a horizontal, cross-sectional view, 35 taken on the line 6—6 of Figure 5.

Figure 7 is a transverse, vertical, sectional 40 view of the upper portion of the tubing catcher and showing another method of securing the slip head to the fishing neck.

Figure 8 is a horizontal, cross-sectional view 45 taken on the line 8—8 of Figure 7, and

Figure 9 is a horizontal, cross-sectional view 50 taken on the line 9—9 of Figure 7.

In the drawings, the numeral 10 designates an 55 elongate tubular mandrel which forms the main support of the tubing catcher. This mandrel may be constructed from a section of the well tubing string A in which the catcher is to be connected, whereby said mandrel will be of the same diameter as the tubing string. The upper end of the mandrel is externally screw-threaded into the lower end of the bore 11 of a fishing neck 12. The tubing string A is threaded into the upper end of said fishing neck, whereby the mandrel is secured to the tubing string. The lower end of the fishing neck 12 is enlarged to form an external collar 13 which is provided with screw threads 14 on its peripheral portion. A slip head 15 having an axial bore 16 through which the mandrel 10 extends, surrounds said mandrel, as is clearly shown in Figure 1. The bore of the slip head is enlarged at its upper end and this enlarged portion 17 is threaded so that the head 15 may be screwed onto the externally 55

threaded collar 13 which is formed at the lower end of the fishing neck 12.

In Figure 1, the external diameter of the mandrel 10 has been shown as substantially 5 equal to the bore 16 of the head 15, but, as will be explained, the size of the mandrel 10 may vary. The mandrel and head are secured to the fishing neck 12, which neck is in turn, fastened to the tubing string A, whereby the mandrel and 10 head are carried by said string. The head 15 is formed with a plurality of inclined faces 18 (Figure 2) and gripping slips 19 are adapted to slide vertically on these faces. Each face 18 is 15 formed with a vertical rib 20 which is adapted to engage a complementary groove 21 formed in the rear face of each slip 19, whereby said slips are guided in their vertical movement on the head 15. When the slips are near the lower end of the head 15, as shown in Figure 1, the 20 gripping teeth 22 provided on the outer surface of said slips, are disengaged from the inner wall of the well casing B. However, when the slips are moved upwardly on the head, the inclined faces 18 on which said slips ride, act to move 25 the slips outwardly in a radial direction, whereby their gripping teeth 22 are engaged with the casing wall. Therefore, it will be seen that so long as the slips remain in a lowered position, the head may move downwardly through the well 30 casing B, but upon upward movement of the slips with relation to the head, the teeth 22 of said slips engage the inner wall of the casing to prevent further downward movement of the head 15.

Each slip is provided with depending ears 23 35 at its lower end and the upper end of a link 24 is pivotally secured to the ears 23. The lower end of each link 24 is pivoted between ears 25 which extend upwardly from a flanged sleeve 26. The sleeve surrounds the lower end of the 40 mandrel and normally rests upon a guide collar 27 which is threaded onto the lower end of the mandrel. A coiled spring 28 is confined between the collar 27 and the flange at the upper end of the sleeve 26 and said spring constantly exerts 45 its pressure to urge the sleeve upwardly. However, the weight of the sleeve, as well as the weight of the slips 19, are sufficient to hold the spring compressed or under tension. The guide collar 27 has an integral nipple 29 depending 50 axially therefrom and this nipple is externally screw-threaded. The bore 29 of the nipple is of substantially the same diameter as the bore of the mandrel 10 which, as has been explained, is of the same diameter as the tubing string A. A 55 coupling collar 30 secures the nipple 29 to the tubing string A and thus it will be seen that the device is connected at any point within a tubing string.

Normally, the parts are in the position shown 60 in Figure 1 and the tubing string may be lowered through the well casing B without interference from the slips 19, which slips are held in their lowered or disengaged position by the weight of said slips, in addition to the weight of the 65 sleeve 26. In the event that the tubing string A should break at any point, a sudden downward movement of the string would result. Since the string is directly connected through the fishing neck 12 and the collar 27 to the mandrel 10, the 70 mandrel will of course move downwardly with the tubing string and as the head 15 is also fastened to the fishing neck 12, said head will move simultaneously with the mandrel. The sleeve 75 26, which has the slips 19 secured thereto by the links 24, is slidable on the mandrel 10 and

sudden downward movement of the mandrel and head, due to the tubing string breaking, will cause the mandrel and head to move downwardly with relation to the sleeve 26, said sleeve remaining stationary because the inertia of the weight of the sleeve 26 will hold the sleeve momentarily stationary. Since the slips 19 are secured to said sleeve, said slips will also be held stationary and the downward movement of the mandrel and head will cause the inclined faces 10 of the head 15 to expand the slips 19 in a radial direction, whereby said slips will engage the wall of the casing B and thereby halt further downward movement of the head, mandrel and tubing string. It is noted that the operation of the 15 tubing catcher is substantially the same as the present type of tubing catcher now on the open market.

So long as the tubing catcher is used within a casing and tubing of the size shown in Figure 20 1, no change is made in said catcher. However, if the device is to be connected in a tubing having a smaller diameter, then the fishing neck 12 and the guide collar 27 are changed so as to accommodate a smaller size tubing. Such change 25 of these parts is disclosed in Figure 3. To make the device adaptable to tubing of a smaller size, the collar 27 is replaced by a collar 27' which is of substantially the same construction as the collar 27, with the exception that its bore 29' 30 is smaller so as to receive the smaller size tubing A'. The connection between the smaller tubing and the collar 27' is exactly the same as that shown in the first form. A mandrel 10' having the same diameter as the reduced size tubing A', 35 is substituted for the mandrel 10 and extends through the sleeve 26 and the head 15. The upper end of the reduced mandrel 10' is threaded into the bore of a fishing neck 12' which is of a smaller size than the fishing neck 12. 40

The use of the reduced mandrel 10' will cause an annular space to be present between the bore 16 of the head 15, and a similar space is formed between said mandrel and the bore 26' of the sleeve 26. In order to prevent a lateral movement of the head and sleeve with relation to the reduced mandrel, due to this clearance space, a bushing 31 surrounds the reduced mandrel 10' and is inserted into the lower end of the bore 16 of the head. This bushing is provided with 50 an external annular groove 32, which groove is engaged by a radial set screw 33 which is threaded through an opening 34 provided in the lower end of the head 15. A similar bushing 35 surrounds the reduced mandrel 10' and is disposed 55 within the upper end of the bore 26' of the sleeve 26, being held in position by a set screw 36 which is threaded through a radial opening 31 in said sleeve. The inner end of the screw 36 engages the annular groove 35' in the bushing 35. 60

With the above arrangement, it will be manifest that by changing the fishing neck 12 and substituting the fishing neck 12' and also by substituting the guide collar 27' for the collar 27, 65 the tubing catcher may be connected in a tubing string having a smaller diameter. The mandrel 10 is of course replaced with the mandrel 10' and the bushings 31 and 35 are inserted within the bore 16 of the head and the bore 26' of the 70 sleeve. The tubing catcher is thus adaptable to be readily applied to tubing of various diameters.

If it is desired to use the tubing catcher within a casing B, which is of a larger size than that dis- 75

closed in Figure 1, then it is only necessary to remove the head 15 from the fishing neck 12. In place of this head, a larger head having an increased diameter to conform to the diameter of the casing is substituted. This larger size head is shown in Figure 3 and fits within a larger diameter casing B'.

It might be desirable in some instances, to omit the screw-threaded connection between the slip head and the fishing neck and in such case a connection between the head and the neck such as is disclosed in Figures 7 to 9, could be employed. In this case, the head 15 is provided with a trio of arcuate recesses 40 in its top. The solid portion 41 between the recesses is undercut or slotted as shown at 42. The fishing neck 43 has its lower end enlarged to form a collar 44 and the lower end of this collar is provided with a plurality of radially extending arcuate lugs 45. These lugs 20 are adapted to fit within the recesses 40 formed in the top of the head. After the lugs have been inserted within the recesses, the fishing neck 43 is rotated so that said lugs enter the undercut slots 42 beneath the solid portion 41 of the head. 25 After the lugs have been engaged beneath the overhanging portions 41, arcuate retaining members 46 are fastened within the recesses 40, so as to prevent rotation of the head with relation to the fishing neck. This arrangement confines the 30 lugs 45 within the undercut recesses or slots 42, whereby the neck and head are fastened together. To disconnect these parts, it is only necessary to remove the retaining members 46 from their respective recesses 40, after which the 35 neck is rotated to move the lugs 45 into alignment with the recesses 40. When this is done, the neck may be raised upwardly and removed from the head. This type of fastening may be substituted in place of the screw threads on the collar 40 13 of the neck 12, which is shown in Figure 1 and either type of fastening is suitable.

In adapting the tubing catcher to a casing of larger size, the forms shown in Figures 1, 3 and 7, require that the entire head 15 be replaced by one of a different size. In Figures 4 to 6, a modified form of the invention is shown, wherein it is not necessary to replace the entire head. In this form the fishing neck 12 having the threaded collar 13 at its lower end is used. Secured to 45 the collar 13 of said neck is an adapter collar 50 which is provided with a depending screw-threaded nipple 51. A slip head 52 has the upper end of its bore enlarged and internally threaded to receive the nipple 51. This head is provided 50 with a plurality of recesses or vertical slots 53 which are spaced equally around said head, as is clearly shown in Figure 6. A vertical plate 54 is insertable within each vertical slot 53 and the outer surface of this plate is inclined at 55 to 55 form the slip expanding surface. The plate dovetails into the slot, whereby outward radial displacement of said plate is prevented. When in place within the vertical recess or slot, each plate rests on a shoulder 56 provided at the lower end 60 of said slot and the upper end of the plate lies flush with the top of the head 52. The collar 50 which is secured to the fishing neck and also to the head 52 overhangs the plate 54 and prevents 65 upward displacement thereof.

70 Each plate is formed with a dovetail rib 57 which engages a complementary groove or recess 58 in the rear face of the slips 19, whereby said slip is guided in its vertical movement on the inclined face 55 of each plate 54. The operation

of this form is exactly the same as the form hereinbefore described.

When the plates 54 are utilized, it is obvious that when the device is to be applied or used in a casing of a larger size, it is only necessary to unscrew the collar 50 from the head 52. The plates 54 may then be removed from their vertical slots 53 and larger plates 59 (Figure 5) substituted therefor, the parts are then returned to the position shown in Figure 5 and the device may be lowered within a larger casing.

It is not essential that the collar 50 be made separately from the fishing neck 12 for, as shown in Figure 5, the fishing neck may be enlarged to form an overhanging collar 59' which retains the 15 plates 59 in position within their respective slots. In such case, the collar 59' which is formed integral with the lower end of the fishing neck has the depending nipple 51' which screws into the head 52. In this latter form, wherein the removable plates are provided, it is manifest that the size of the tubing may be changed merely by changing the fishing neck and substituting a fishing neck having a smaller bore to accommodate the smaller tubing. A smaller tubing string is 20 shown connected to this form in Figure 5 and as will be seen by observing this figure, the bushings 25 34 and 35 are employed in the same manner as in the first form.

From the foregoing, it will be obvious that a 30 tubing catcher which is readily adaptable for use in casing and tubing of varying diameters is provided. The change in the tubing catcher may be accomplished quickly and easily and the gripping slips, as well as the sleeve 26 which carries said 35 slips, are used in all forms regardless of the size of the casing or tubing. By providing a tubing catcher of this type, it is evident that it is not necessary that a tubing catcher be provided for each particular size of tubing and casing.

40 What I claim and desire to secure by Letters Patent is:

1. A tubing catcher for a well tubing string including, a tubular mandrel, a connection in the well tubing string adapted to detachably receive 45 the upper end of the mandrel, a second connection in the string for receiving the lower end of the mandrel, whereby the mandrel forms a part of and is detachably connected in the string, a slip head having a bore through which the mandrel extends, said head being carried by the upper connection, expansible slips mounted on the head and arranged to be expanded when the head is moved downwardly with relation to said slips, the diameter of the mandrel being less than the 50 diameter of the bore, and means insertable within the bore of the head for holding said mandrel in axial alignment with said bore.

2. A tubing catcher for a well tubing string including, a tubular mandrel, a connection in the 60 well tubing string adapted to detachably receive the upper end of the mandrel, a second connection in the string for receiving the lower end of the mandrel, whereby the mandrel forms a part of and is detachably connected in the string, a 65 slip head having a bore through which the mandrel extends, said head being carried by the upper connection, expansible slips mounted on the head and arranged to be expanded when the head is moved downwardly with relation to said 70 slips, the diameter of the mandrel being less than the diameter of the bore, and means insertable within the bore of the head for holding said mandrel in axial alignment with said bore, the slip head being detachably connected with the up- 75

per connection whereby said head may be removed and replaced by one of a different size.

3. A tubing catcher for a tubing string including, a tubular mandrel, a fishing neck having a threaded bore for receiving the upper end of the mandrel, a guide collar threaded onto the lower end of the mandrel, said neck and collar being arranged to also receive the well tubing whereby the mandrel is connected in the tubing string, a slip head having a bore through which the mandrel extends directly threaded onto the fishing neck and movable therewith, and gripping slips slideable on said head normally in a retracted position on said head and adapted to be moved to an expanded position when the head is moved with relation to said slips.

4. A tubing catcher for a tubing string including, a tubular mandrel, a fishing neck having a threaded bore for receiving the upper end of the mandrel, a guide collar threaded onto the lower end of the mandrel, said neck and collar being arranged to also receive the well tubing whereby the mandrel is connected in the tubing string, a slip head having a bore through which the mandrel extends directly threaded onto the fishing neck and movable therewith, gripping slips slideable on said head normally in a retracted position on said head and adapted to be moved to an expanded position when the head is moved with relation to said slips, threaded connections between the mandrel and fishing neck and guide collar and means insertable within the bore of the head for holding said mandrel in axial alignment with said bore.

35 5. A tubing catcher for a tubing string including, a tubular mandrel, a fishing neck having a threaded bore for receiving the upper end of the mandrel, a guide collar threaded onto the lower end of the mandrel, said neck and collar being arranged to also receive the well tubing whereby the mandrel is connected in the tubing string, a slip head having a bore through which the mandrel extends directly threaded onto the fishing neck and movable therewith, expandable slips mounted on the head, and a sleeve surrounding the lower end of the mandrel and connected with the slips for holding the slips momentarily stationary upon sudden downward movement of the head, whereby said head may move downwardly with relation to the slips to expand said slips.

6. A tubing catcher for a tubing string including, a tubular mandrel, a fishing neck having a threaded bore for receiving the upper end of the mandrel, a guide collar threaded onto the lower end of the mandrel, said neck and collar being arranged to also receive the well tubing whereby the mandrel is connected in the tubing string, a slip head having a bore through which the mandrel extends threaded onto the fishing neck, expandable slips mounted on the head, a sleeve surrounding the lower end of the mandrel and connected with the slips for holding the slips momentarily stationary upon sudden downward movement of the head, whereby said head may

move downwardly with relation to the slips to expand said slips, the size of the mandrel being less than the diameter of the bore, and means insertable within the bore of the head and within the bore of the sleeve for holding said mandrel in axial alignment with the head and sleeve.

7. A tubing catcher including, a tubular mandrel adapted to be connected in a tubing string, a slip head surrounding said mandrel, removable guide plates mounted on said head, and expandable slips mounted on said plates are arranged to be expanded radially of the mandrel and head when the head is moved downwardly of the slips.

8. A tubing catcher including, a tubular mandrel, a connection in the well tubing string adapted to detachably receive the upper end of the mandrel, a second connection in the string for receiving the lower end of the mandrel whereby the mandrel is detachably connected in the tubing string, a slip head surrounding the mandrel and having vertically extending recesses in the outer surface, guide plates removably mounted in the recesses and having their outer surfaces inclined to form slip expanding surfaces, and gripping means slideable on said slip expanding surfaces.

9. A tubing catcher including, a tubing string, an elongate tubular mandrel having its lower end connected by screw threads in said tubing string, a coupling element carried by the tubing string and having a bore for receiving the upper end of the mandrel whereby said mandrel forms a part of said string and is detachably connected therein, a slip head surrounding the mandrel and having its upper end secured directly to the exterior of the coupling element, and gripping slips slideable on said head normally in a retracted position on said head and adapted to be moved to an expanded position when the head, mandrel and tubing string are moved relative to said slips.

10. A well tool including, a body having an axial bore therethrough, anchoring elements carried on the body, a mandrel disposed in the bore of the body and having its upper end screw-threaded, the body having a countersunk internally screw-threaded recess in its upper end surrounding its bore, and a removable fishing neck having an annular base screw-threaded internally and externally and screwed onto the upper end of said mandrel and into the recess of the body to immovably connect the neck and body.

11. In a well tool, the combination of an elongated tubular mandrel, a head having a bore therethrough through which the mandrel extends and in which the mandrel is removably disposed, anchoring elements slideable vertically on the head, an actuator slidably mounted on the mandrel, connections between the anchoring elements and the actuator, and a fishing neck having screw-threaded engagement with the upper end of the head and mandrel for removably holding them in rigid relation with each other.

HOMER H. HALL.
